US0D1019655S

(12) **United States Design Patent** (10) **Patent No.:** **US D1,019,655 S**
(45) **Date of Patent:** **** Mar. 26, 2024**

(54) **PROTECTIVE CASE**

(71) Applicant: **GETAC TECHNOLOGY CORPORATION**, New Taipei (TW)

(72) Inventors: **Wei-Sen Lu**, Taipei (TW);
Cheng-Hung Chiang, Taipei (TW)

(73) Assignee: **GETAC TECHNOLOGY CORPORATION**, New Taipei (TW)

(**) Term: **15 Years**

(21) Appl. No.: **29/815,168**

(22) Filed: **Nov. 11, 2021**

(51) LOC (14) Cl. **14-02**

(52) U.S. Cl.
USPC **D14/440**

(57) **CLAIM**

The ornamental design for a protective case, as shown and described.

DESCRIPTION

FIG. 1 is a top, front, and right side axonometric view of a first embodiment of a protective case, showing our new design;

FIG. 2 is a bottom, rear, and left side axonometric view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top, front, and right side axonometric view of a second embodiment of the protective case, showing our new design;

FIG. 10 is a bottom, rear, and left side axonometric view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.
